Telecomunicazioni Siemens S.p.A., Milan, Italy

Filed Oct. 9, 1963, Ser. No. 76,924

Claims priority, application Italy Apr. 10, 1963

Term of patent 14 years

(Cl. D26—14)

FIG 1

FIG 2

FIG 3

FIG 5

FIG 4

FIG. 6

FIG. 7

FIG. 8

FIG. 1 is a side elevational view of a telephone set, showing my new design in closed position, the opposite side being substantially a mirror image thereof;

FIG. 2 is a top plan view;

FIG. 3 is a bottom plan view;

FIG. 4 is a rear elevational view as seen from the right in FIG. 1;

FIG. 5 is a front elevational view as seen from the left in FIG. 1;

FIG. 6 is a side elevational view in open position;

FIG. 7 is a top plan view in open position; and

FIG. 8 is a bottom plan view in open position.

I claim:

The ornamental design for a telephone set, as shown and described.
